UNITED STATES PATENT OFFICE.

ANTON I. SANDBO, OF ROCK ISLAND, ILLINOIS.

VAPORIZER.

1,251,582.

Specification of Letters Patent. Patented Jan. 1, 1918.

Application filed February 9, 1917. Serial No. 147,668.

To all whom it may concern:

Be it known that I, ANTON IVER SANDBO, a citizen of the United States, residing at Rock Island, in the county of Rock Island and State of Illinois, have invented certain new and useful Improvements in Vaporizers; and I do hereby declare the following to be a full, clear, and exact description of the invention, such as will enable others skilled in the art to which it appertains to make and use the same.

This invention relates to a vaporizer and has for its primary object to provide a device of this character which when applied to an intake pipe of an internal combustion engine and ignited, will produce a sufficient amount of heat to thoroughly heat the intake pipe and thus form a heating and vaporizing medium for any fluid that may pass through it.

A further object of the invention is to provide the carburetor hot air intake pipe with an aperture and to snugly position the vaporizer around said pipe and over said aperture therein, whereby when the vaporizer is ignited, the flame will pass upwardly into the hot air pipe through the aperture therein, the flame being utilized as a heating medium in addition to the exhaust pipe of the motor to effectively heat the air within the hot air intake pipe.

With these and other objects in view as will appear as the description proceeds, the invention comprises the various novel features of construction, combination and arrangement of parts as will be more fully described hereinafter and set forth with particularity in the appended claims.

Referring to the drawings:

Figure 1 is a side elevation of an internal combustion engine showing my improved vaporizer attached to the carburetor hot air intake pipe.

Fig. 2 is a vertical sectional view taken on the line 2-2 of Fig. 1.

Fig. 3 is a horizontal sectional view taken on the line 3-3 of Fig. 2.

Fig. 4 is a side elevation of an intake manifold showing another form of my vaporizer attached thereto.

Fig. 5 is a horizontal sectional view taken on the line 5-5 of Fig. 4.

Fig. 6 is a side elevation of the upper portion of an internal combustion engine showing another form of vaporizer attached thereto, and,

Fig. 7 is a detail perspective view of this form of vaporizer.

Similar characters of reference are used to denote like parts throughout the following description and the accompanying drawings.

Referring more particularly to the drawings the numeral 1 represents the outer wall of the vaporizer and as shown in Fig. 3 is substantially semi-circular in cross sections, the vertical side edges of the wall being curved inwardly as indicated by the numeral 2 and terminate in parallel projecting ears 3 which are designed to be clamped together so as to hold the device in position upon the hot air intake pipe 4 by a clamping bolt 5. The upper end of the outer wall 1 is curved inwardly as indicated by the numeral 6 so that it will snugly fit the outer circumference of the intake pipe.

The device also embodies an inner wall 7 which is arranged in spaced relation to the outer wall and is also of semi-circular formation in order to snugly fit the circumference of the hot air intake pipe 4. This inner wall 7 is connected to the outer wall by a bottom wall 8 to form a trough in which is arranged a suitable amount of waste or packing 9.

As shown, the inner wall is about half the height of the outer wall, and the outer wall is provided circumferentially at points below the upper edge of the inner wall with air inlet openings 10. The hot air intake pipe is provided adjacent the upper end of the outer wall with an intake opening 11.

From the above description it will be apparent that in order to facilitate an easy and ready starting of the engine, that it is simply necessary to saturate the waste 9 with a suitable combustible liquid and ignite the same, whereupon the flame and heat will pass upwardly through the inlet openings 11 in the hot air pipe 4 and serve to effectively heat the air passing through said pipe.

The flame is caused to take this upward course through the device and hot air pipe 4 by reason of the air holes 10 which serve to create a draft through the device. It will also be noted that by virtue of the inner wall projecting above the air holes 11, and the holes through which the combustible liquid is introduced, that it will be impossible for the liquid to flow over the upper edge of the inner wall.

In Figs. 4 and 5 it will be seen another

form of vaporizer which is designed to be attached around the vertical stand pipe 12 of the intake manifold 13, so that the flame from the device will pass upwardly around 5 the stand pipe 12 and serve to heat the same to thoroughly vaporize the hydrocarbon in its passage through the intake manifold.

This form of device is shown to consist of a pair of semi-circular sections 14 which 10 are secured together around the stand pipe 12 by bolts 15. This form of device in other respects is substantially the same as that hereinbefore described, with the exception that the top of this device is open as clearly 15 shown in Fig. 5, so that the flame can freely ascend around the stand pipe 12.

Each of these sections 14 are provided circumferentially and at points below the upper edge of the inner wall 16 with air 20 draft openings 17.

In Figs. 6 and 7 will be seen another form 25 of vaporizer, and is shown to consist of an elongated trough 18 that is attached to one of its upper side edges an offset and upwardly projecting supporting arm 19 that is provided in its upper with an opening 20 whereby the device may be positioned over the outer end of one of the studs 21 and securely held in place by the usual clamping 30 nut 22 carried thereby and also serving to hold the manifold clamping yokes 23 in position. By reason of the supporting arm 19 being offset from the trough 18, it will support the trough in position immediately 35 beneath the oppositely extending portions 24 of the intake manifold 25.

A wick or other suitable means is positioned within the trough 18 and designed to be saturated with a combustible liquid and 40 subsequently ignited to produce a flame and

sufficient heat to heat the intake manifold and thoroughly vaporize the hydrocarbon in its passage therethrough.

What I claim as new is:

1. The combination with an intake pipe, 45 of a vaporizer adapted to be attached thereto and comprising inner and outer walls, a bottom wall connecting said inner and outer walls to form a trough, said inner wall being half the height of the outer wall, and 50 said outer wall being provided at points below the upper edge of the inner wall with air inlet openings, and a wick arranged within the said trough between the inner and outer walls. 55

2. The combination with the carburetor hot air intake pipe having an opening therein, of a vaporizer adapted to be attached to said intake pipe over said opening and comprising inner and outer walls, 60 the outer wall having its upper end curved inwardly so as to snugly fit the circumference of the intake pipe, said wall being provided adjacent its lower end with air inlet openings, a bottom wall connecting said 65 inner and outer walls to form a trough, and a wick arranged within said trough and adapted to be saturated with a combustible liquid, whereby when it is ignited, the flames will pass upwardly of the vaporizer and 70 into the hot air intake pipe through the opening therein.

In testimony whereof I have signed my name to this specification in the presence of two subscribing witnesses.

ANTON I. SANDBO.

Witnesses:

FRED GRUBY,
CHAS. GINNANE.
